Attorney

UNITED STATES PATENT OFFICE.

ORLA L. HUFFMAN, OF WEATHERFORD, TEXAS.

WASHING-MACHINE.

1,378,541.

Specification of Letters Patent. Patented May 17, 1921.

Application filed January 27, 1920. Serial No. 354,442.

To all whom it may concern:

Be it known that I, ORLA L. HUFFMAN, a citizen of the United States, residing at Weatherford, in the county of Parker and 5 State of Texas, have invented certain new and useful Improvements in Washing-Machines, of which the following is a specification, reference being had to the accompanying drawings.

10 This invention relates to certain improvements in washing machines and has relation more particularly to an operating mechanism for a dolly comprised therein, and it is an object of the invention to provide 15 a novel and improved mechanism of this general character wherein the dolly is caused to alternately rotate in reverse direction.

Another object of the invention is to provide 20 a novel and improved mechanism of this general character embodying a driven shaft having universal movement independently of its rotation and which shaft is provided with a pinion coacting with the 25 opposite faces of a rack carried by a member supported for reciprocatory movement wherein the rotation of said shaft imparts reciprocation to the member, together with means for operatively connecting the lubricating 30 member with a dolly of a washing machine or other rotary member for supporting rotation thereto alternately in reverse direction.

The invention consists in the details of 35 construction and in the combination and arrangement of the several parts of my improved washing machine whereby certain important advantages are attained and the device rendered simpler, less expensive and 40 otherwise more convenient and advantageous for use, as will be hereinafter more fully set forth.

The novel features of my invention will hereinafter be definitely claimed.

45 In order that my invention may be the better understood, I will now proceed to describe the same with reference to the accompanying drawings, wherein:

Figure 1 is a view partly in elevation and 50 partly in section illustrating a washing machine having applied thereto an operating mechanism constructed in accordance with an embodiment of my invention; and

Fig. 2 is a fragmentary view partly in 55 elevation and partly in section of the structure disclosed in Fig. 1, the line of section

being substantially at right angles to the line of section in Fig. 1.

As disclosed in the accompanying drawings, T denotes a tub of desired dimension 60 and configuration and which is herein disclosed as mounted upon a table A or other supporting structure. Extending within the upper portion of the table T and supported for rotary movement is a dolly D. 65 Coacting with the dolly D is a rack 1 capable of reciprocatory movement. Pivotally engaged with one end of the rack 1 is an end portion of a link 2. The opposite end portion of the link 2 is pivotally engaged 70 with a vertically disposed rock lever 3. herein disclosed as supported intermediate its length by a bracket 4 carried by the side wall of the tub T.

Pivotally engaged with the lower end portion of the lever 3 is a link 5 extending inwardly and below the tub T and said link is also pivotally engaged with an extension or arm 6 carried by an end portion of a plate 7. In the present embodiment of my 80 invention, the plate 7 has its flat faces vertically disposed and is slidably supported in the guides 8 carried by the plate 9 depending from the table or support A. Extending outwardly from a face of the plate 7 is a 85 plurality of pins or fingers 10 equidistantly spaced in a direction longitudinally of the plate 7 and which pins or fingers 10 provide a rack with which coacts from below and above a pinion 11. 90

The pinion 11 is carried by an end portion of a driven shaft 12 having universal connection, as at 14, with a driving shaft 15, or the like. As the means for operating the shaft 15 forms no part of my present 95 invention, a detailed description and illustration of such means is not believed to be necessary.

The shaft 12 extends beyond the pinion 11 and freely mounted upon the extended 100 portion of the shaft 12 is a roller bearing or sleeve 16.

The portion of the shaft in close proximity to the pinion 11 is disposed through a slot 17 having its longitudinal axis perpendicularly related to the rack as afforded by the pins or fingers 10. 105

In the present embodiment of my invention, the slot 17 is produced in an arm or bracket 18 depending from the table or support A. By this means, it will be perceived that the shaft 12 is held by the arm or 110

bracket 18 against lateral movement in a direction longitudinally of the rack carried by the plate 7 but is capable of limited swinging movement lengthwise of the slot 5 17. When the shaft 12 is in its lowermost position, the pinion 11 meshes or coacts with the rack or pins 10 from below so that as the shaft 12 rotates, the plate 7 is caused to mesh in one direction and which movement 10 through the instrumentality of the lever 3 imparts rotary movement to the dolly D in one direction.

Adjacent each end of the plate 7 are the substantially semicircular trackways 19 having their bows disposed in a direction away from the fingers or pins 10. These trackways, however, are positioned in such proximity to the end pins or fingers 10 to be engaged by the roller bearing or sleeve 16 so 20 that the shaft 12 will be elevated to cause the pinion 11 to mesh with the fingers or pins 10 from above when the plate reaches the end of its stroke in one direction or to permit the shaft 12 to drop to engage the 25 pins or fingers 10 from below when the plate 7 reaches the end of its stroke in the opposite direction. By this means, it will be readily seen that the reciprocation of the plate 7 results in the dolly D or other rotatable member to be alternately rotated in 30 opposite direction.

From the foregoing description, it is thought to be obvious that a washing machine constructed in accordance with my 35 invention is particularly well adapted for use by reason of the convenience and facility with which it may be assembled and operated, and it will also be obvious that my invention is susceptible of some change and 40 modification without departing from the principles and spirit thereof, and for this

reason I do not wish to be understood as limiting myself to the precise arrangement and formation of the several parts herein shown in carrying out my invention in practice except as hereinafter claimed. 45

I claim:

In combination with a body, means for supporting said body at an elevation, a vertically disposed rotatable member carried by said body and extending thereabove, a vertically disposed rock lever supported by the body to one side thereof, a rack slidably supported upon the body and coacting with the rotatable member to rotate said member upon reciprocation of the rack, an operative connection between the lever and the rack whereby the rack is reciprocated upon swinging movement of the lever, a plate depending from the bottom of the body, a second plate supported for slidable movement by the first named plate, a plurality of aligned pins projecting outwardly from the second plate, arcuate guide members carried by said second plate adjacent the end pins, a bracket depending from the bottom of the body and provided with a vertically disposed slot, a rotatable and vertically oscillating shaft extending through the slot of the bracket, a pinion carried by the shaft for engagement with the pins, said shaft extending beyond the pinion for contact with the arcuate guide members, whereby said pinion engages the pins from above and below, and a link connecting the second named plate and the lower end portion of the lever so that the reciprocation of the plate by the pinion 11 rocks the lever. 50 55 60 65 70 75

In testimony whereof I hereunto affix my signature.

ORLA L. HUFFMAN.
